CASK.

1,133,688.

Specification of Letters Patent. Patented Mar. 30, 1915.

Application filed October 25, 1913. Serial No. 797,156.

To all whom it may concern:

Be it known that we, HENRY C. WIEDEMAN and FRANK A. SCHAUM, citizens of the United States, residing at Detroit, county 5 of Wayne, State of Michigan, have invented a certain new and useful Improvement in Casks, and declare the following to be a full, clear, and exact description of the same, such as will enable others skilled in 10 the art to which it pertains to make and use the same, reference being had to the accompanying drawings, which form a part of this specification.

This invention relates to casks or kegs, 15 and especially to containers for beer and other beverages, and has for its object a special form of head construction used in connection with such a cask, as is shown in the application of Messrs. Huetteman, 20 Cramer, Wiedeman and Schaum Serial No. 687,906. Some of the features might be used with casks of different construction with advantageous results.

Figure 1, is a fragmentary end-view of 25 the cask, showing parts broken away for clearer illustration. Fig. 2, is a fragmentary view partly in side-elevation and partly in vertical section. Fig. 3, is a detail of the cap before it is spun into the angle 30 between the chime and the head.

A peculiar feature of the Huetteman, Cramer, Wiedeman and Schaum cask is the use of compressed cork staves *a* and a metallic stave-sheath *b* with in-turned flanges at 35 the sides as shown at *c*. The staves *a* are packed about a container *d* which is preferably glass-enamelled. By forcing the hoops *e* down upon the stave-sheaths these members are constricted to force the pressed ground- 40 cork staves *a* closely together and also closely in contact with the container *b*. This results in a package which is thoroughly heat insulated, and which is also elastic so as to be capable of taking blows and shocks 45 without injury to the exterior casing or the inner container.

The present invention consists in an improved head construction for such a cask. This head construction comprises a head 50 sheathing *f* that consists of a single piece of sheet metal about $\frac{1}{2}$ inch thick, which covers not only the head of the cask but also folds over the ends of the staves and stave

sheaths as a protecting cover for them. This sheathing is first pressed into a cap (as 55 shown in Fig. 3) by suitable dies. The cap can be slipped over the end of the cask so that the annular flange *g* of the cap fits over the outside of the chime. The cap is then forced down into the angle between the inside of the chime and the head. This is accomplished by spinning the metal disk of the cap by a suitable spinning tool. The cap is then welded to the metallic stave 60 sheath structure or may be secured by other 65 suitable means. In order to protect the stave ends and also the head sheathing, which is rather thin metal, a reinforcing ring *i* is employed. This reinforcing ring 70 sets directly upon the top of the staves and stave sheaths and serves to take the knocks and blows which are given the barrel upon its end. The reinforcing ring is made of heavy metal, preferably $\frac{1}{4}$ inch thick.

It has been found very essential in a glass- 75 enameled cask to prevent the ends of the container warping in and out, either by gas pressure generated by the contents or by a blow from the exterior, for if the ends are allowed to warp they will crack the enamel. 80 To avoid this and yet secure the advantages of an elastic heat-insulated cask, the head of the cask is made in two pieces, comprising a disk of ground pressed cork *j* which rests directly upon the head of the container. 85 This acts as a cushion and also as a heat insulator. Above this is placed a rigid head *k* which gives stiffness to the head of the cask and prevents the warping of the head of the container and also protects the container 90 from blows or knocks received by the cask. We prefer to use wood, but a composition material that is both rigid and somewhat of a heat insulator might be employed. This rigid head does not come directly in contact 95 with the metal of the container so as to injure the container when a severe blow is received on the end of the cask, as from dropping the same or otherwise. The pressed ground-cork disk cushions the rigid member with respect to the metallic container.

What we claim is:

The combination, with a cask provided with a side structure of soft insulating substance extending beyond the heads of the cask, and suitable heads for the cask, of

stave sheaths constructed of sheet metal and fitted together to protect the said soft insulating material, the said stave sheaths extending beyond the heads of the cask, a flat reinforcing ring constructed of heavy stiff metal and adapted to overlie the ends of the filler material and the stave sheaths, and a protecting covering of sheet metal folded over the outside of the ends of the metal

stave sheaths and over the said reinforcing ring and fitted into the chime of the cask.

In testimony whereof, we sign this specification in the presence of two witnesses.

HENRY C. WIEDEMAN.
FRANK A. SCHAUM.
